CLAIM

The ornamental design for an automatic cooker as shown and described.

DESCRIPTION

FIG. 1 is a front, top perspective view of an automatic cooker, showing my new design;

FIG. 2 is a left side view thereof;

FIG. 3 is a top view thereof;

FIG. 4 is a top, front, left side perspective view thereof;

FIG. 5 is a top, front perspective view thereof; and,

FIG. 6 is a front view thereof.

The word 'GREENPAN' appears in the drawings as an ornamental feature forming part of the claimed design and is a registered trademark of Apollo Topco, a besloten vennootschap (b.v.) organized under the laws of Belgium.
